UNITED STATES PATENT OFFICE.

ALLAN L. EATON, OF AUSTIN, ILLINOIS, ASSIGNOR TO CHARLES W. SHONK COMPANY,
OF CHICAGO, ILLINOIS, A CORPORATION OF NEW JERSEY.

SECTIONAL DISPLAY-CABINET.

1,154,240.

Specification of Letters Patent. Patented Sept. 21, 1915.

Application filed December 23, 1912. Serial No. 738,113.

To all whom it may concern:

Be it known that I, ALLAN L. EATON, a citizen of the United States, residing in Austin, in the county of Cook and State of Illinois, have invented a new and useful Improvement in Sectional Display-Cabinets, of which the following is a specification.

This invention relates to an improvement 10 in sectional display shelves or cabinets, especially intended for the display of such goods as crackers contained in cans having a transparent side or end.

The invention consists in the novel construction and devices and combinations of parts and devices hereinafter more specifically set forth and made the subject matter of claim.

In the accompanying drawing which 20 forms a part of this specification, Figure 1 is a front elevation of one of the improved cabinets, consisting of two sections united together. Fig. 2 is a cross section of the upper portion of Fig. 1 on the line 2—2, and Fig. 3 is a sectional view, taken on the line 3—3 of Fig. 2.

Each of the sections or individual shelves consists of the following parts: two end pieces A, A, each having its upper and 30 lower edges flanged with the flanges a , a^1 , and its rear edge flanged with the flange a^2 . These two end pieces are rigidly connected together by the inclined shelf B, having the front, downwardly depending curtain B^1 , and the rear, upwardly extending wall B^2 , both the curtain and the wall being flanged with the strengthening flanges b^1 , b^2 , the inclined shelf, the depending curtain and the back wall being each formed with a 35 flange b^3 by means of which, by aid of bolts and nuts or rivets b^4 , the shelf structure is rigidly united to both of said end pieces. At the rear, and extending diagonally from the upper part of the end pieces to the 45 lower part of the end pieces are the diagonal braces C, bolted or riveted by the fastenings c, to the rear flanges a^2 of the end pieces, and secured to each other at the center by the fastening c^1 . A top D is 50 stamped up out of the sheet metal with an imperforate top and depending sides and ends d and an inturned flange d^1 at each of its ends. This top is removably secured to the cabinet by thumb nuts E, E. Where two

or more shelves are used, one above the other, it is only necessary or desirable that the upper one shall be provided with the top or cover, and in that case, the upper shelf structure or section may be secured to the lower one by the thumb nuts E. The structure may thus consist of a single section or shelf or two or more sections or shelves placed one upon the other to any desired height or extent, after the manner of well known sectional book shelves.

At Fig. 2 is shown one of the glass sided cracker boxes F, placed in position. The shelf should be long enough to accommodate a certain number of these boxes placed far enough asunder from each other so that 70 they may be readily removed or handled.

The entire structure, it will be noted, is made of sheet metal; can be shipped in the knock-down, if desired; can be easily erected; can be increased in capacity when 75 that is needed; and is cheap, durable and efficient. The open back of the structure affords an extremely convenient means of reaching the contents of the shelves, as for dusting, without the removal of the cracker 80 boxes.

The inclination of the shelves may be varied to suit the special kind of goods to be displayed. For some purposes, a less inclination from that shown in the drawings 85 would be desirable.

Although the structure is adapted to be shipped in the knock-down, to be set up at the receiving point ready for use, it is strong and substantial enough to be shipped 90 in the erected form, if that is desired, as will sometimes be the case.

I claim:—

In a display case of the character described, a section comprising two flanged, 95 sheet metal end pieces secured together by a longitudinal shelf, the latter having a vertically extending front portion, a downwardly and rearwardly inclined intermediate portion and an upwardly and rearwardly inclined inner portion, said shelf forming means for supporting cans in an inclined position, substantially as specified.

ALLAN L. EATON.
